LABELING MECHANISM.

1,418,455.

Specification of Letters Patent. Patented June 6, 1922.

Application filed November 23, 1920. Serial No. 425,890.

To all whom it may concern:

Be it known that we, JOHN A. OLSON and JOHN E. WILLIAMSON, citizens of the United States, and residents of Bergenfield and 5 Yonkers, in the counties of Bergen and Westchester, and States of New Jersey and New York, respectively, have invented certain new and useful Improvements in Labeling Mechanism, of which the following is a 10 specification.

The invention relates to mechanism for applying labels or other sheet material, usually paper, to articles or packages, and for feeding or conveying the packages.

15 More particularly the invention relates to means for securing labels to packages, such means being adapted at the same time to advance the packages on which the labels are secured.

20 In the present adaptation the invention provides means for smoothing down and pressing upon a row of similar articles labels which have been previously initially affixed to the articles, and at the same time feeding successive rows of the articles forward.

25 More particularly described, an important feature of the invention consists in smoothing and pressing devices which smooth the ends of labels down upon the sides of packages and at the same time yieldably grip the packages and move them successively from one position to another. In a preferred form as shown herein movable brush devices are employed which smooth down 30 and affix to the packages adhesively coated labels and at the same time advance the packages in a desired direction. Very simple and effective means are thus provided for performing the desired functions.

35 The invention also includes improved means for imparting a step by step movement to a suitable conveyor and means for positively retaining the conveyor in stationary position between its movements. The 40 invention also comprises other instrumentalities and combinations of parts.

45 The characteristics and advantages of the invention are sufficiently explained in connection with a detail description of the accompanying drawings which show exemplifying embodiments of the invention. After 50 considering these, persons skilled in the art will understand that many variations and modifications may be made in the different

instrumentalities, as well as in the general arrangement and sub-combinations of parts; and we contemplate the employment of all embodiments of the invention which are within the scope of the claims.

55 In the drawings:

Fig. 1 is a front elevation of labeling mechanism embodying the invention;

Fig. 2 is a left end elevation of Fig. 1, with certain parts in vertical section;

Fig. 3 is a fragmentary sectional view 65 showing the parts in another operative position;

Fig. 4 is an end elevation of modified mechanism; and

Fig. 5 is a detail showing the modified 70 mechanism in another operative position.

A table 10 which may be continuous or sectional is supported by suitable framing 11. A conveyor 12, consisting in this instance of the upper flight of a continuous 75 conveyor belt, passes over the table and is moved step by step toward the left, as indicated by the arrow. The conveyor is provided with suitable blades 13 arranged at regular intervals for advancing successive 80 rows of articles, represented in this case by cigarette packages P. A row of packages is represented in the right hand portion of Fig. 1 after it has been placed upon the conveyor in proper position, with a conveyor 85 blade 13 engaging the rear side of the rear-most package in the row, ten packages being conveniently arranged in each row to conform to customary methods of boxing cigarette packages. Evidently the number of 90 packages in a row may be varied and the principles of the invention also apply to cases in which only a single package is operated upon at a time.

Mechanism X is shown in dotted lines 95 which places successive rows of packages upon the conveyor during its intervals of rest and also applies to the top of each package an adhesively coated label L, the ends of which extend outward from each 100 side of the package, as shown in Fig. 2. This initial label attaching and row feeding mechanism does not form a part of the present invention, but is shown in proper relation to the invention mechanism to illustrate the adaptation of the present invention to representative mechanisms for supplying packages with initially attached 105

labels in a suitable manner. The present invention is equally available when packages or package rows with initially attached labels are placed upon the conveyor, substantially at the position X, by hand.

At the left in Fig. 1 is mechanism embodying the present invention for completing the label attachment, by smoothing down the ends against the sides of the packages, and 10 advancing the packages usually in a direction away from the conveyor, to other mechanism which performs other operations upon the articles, in the present instance the additional operation consisting in packing 15 the cigarette packages in boxes, or in arranging them suitably for such packing.

The conveyor passes below vertical guides 15 consisting of upright members having 20 openings 16, centered in relation to the position of each package in a package row located in the left hand position of Fig. 1, these openings extending from the tops of the guide members to a point somewhat above the bottoms of the packages. The 25 side members are provided with angularly extended bases 17 connected to the table. There is thus formed a trough or channel which guides the package rows against lateral displacement and provides openings 16 30 for the accommodation of the combined label smoothing and feeding brushes.

Located above the table at the left hand package row position of Fig. 1 is a substantially rectangular brush frame 20 enclosing 35 the combined brushing and feeding devices. These comprise vertical side members 21 which constitute in effect brush bodies and are of any suitable material to conveniently receive groups of brush bristles 22. These 40 bristles are arranged in vertical rows and may cover substantially the entire faces of the brush members confronting the package rows, or sufficient bristles may be omitted near the bottoms of the bodies to provide 45 bristle clearance for the portions of guide members 15 intermediate the opening 16. Certain rows of bristles at the lower ends of the brush bodies are arranged to extend 50 down into these openings and the bristle arrangement is such that at least the longitudinal dimension of the labels in the direction of the length of the package row is 55 covered by bristle ends throughout the vertical length of the brushing means. The ends 60 of the brush bodies are connected by suitable end members 24, these together with the brush bodies forming substantially a rectangular box-like enclosure for successive package rows, lined on the two main sides 65 with brush bristles. The side and end members of this enclosure are connected to frame 20 by screws 25 or otherwise, as may be convenient.

The groups of bristles are arranged in 65 the brush bodies so that the individual bris-

ties are mainly inclined inwardly and upwardly.

Frame 20 is carried by an upright 30 bolted to the frame at 31 and this upright passes through vertical guide members 31 70 secured to a side member of the frame. Frame 20 is reciprocated vertically at suitable intervals in relation to the conveyor movement by mechanism later described. When the conveyor brings a row of packages to rest in the left hand position of Fig. 1 the brush frame is elevated as shown in Fig. 2 and is then moved down to the position of Fig. 3, certain lower rows of bristles in this movement passing into openings 16 80 of guides 15 and suitable rows of bristles engaging faces of the upper surfaces of the laterally extending ends of the labels L and turning these ends down against the sides of the packages, and successive groups of 85 bristles then brushing and pressing the label ends into firm adhesive engagement with the package sides, until the downward limit of brush movement is reached. The brush frame is then raised and owing to the angular arrangement of the bristles they at 90 once firmly grip the sides of the packages and raise the package row until when the brush frame is again in elevated position as shown in Fig. 2, the package row last 95 brushed and elevated is in the lowermost position between the brush members. The package row is there held with satisfactory 100 security by the brush bristles, but is freely movable vertically in relation to the brush members by reason of the relative ease of deflection of the bristles in an upward direction, owing to their angular arrangement.

The conveyor 12 then moves forward another step, bringing another row of articles 105 into position; the brush frame again descends and brushes down the labels in the new row in the same manner and at the same time the lowermost row of packages between the brush members engages the upper ends 110 of the new package row and is prevented from moving farther downward and is in effect pushed up between the brush members until at the termination of the downward brush movement the new package row 115 is fully inserted between the brushes and the row last operated on lies above the new row. In the continued upward feeding due to the brush frame movement the package row is acted upon by successive sets of 120 bristles and the label ends are held securely, smoothed down and pressed against the sides of the packages, and at the same time in each package row position the packages are securely held against return movement by 125 appropriate bristle groups. Fig. 2 shows the combined brush and feeding device after several operations sufficient to substantially "fill" the brush members with vertically superposed rows of packages. At the next 130

- downward movement the uppermost row of packages is ejected from between the brush members and may be removed in any suitable way. It is preferred to provide means for automatically removing the successively discharged package rows. For this purpose a carry-off conveyer 40, which may be an endless belt conveyor with one end supported by a belt roll 41 carried by uprights 42, connected to the table, is provided, with its receiving end located adjacent to and slightly below the upper end of the brush mechanism when in its downward position, as shown in Fig. 3. The brush mechanism 10 is preferably provided with a deflector 45 which may conveniently be of sheet metal, having a longitudinal angular part 46 and laterally extending end members 47, which may be secured to the brush bodies by screws 48, or otherwise. As the uppermost package row is ejected from between the brush bristles the upper ends of the packages strike the angular deflector 46 and are turned outward at about the time that the 20 lower ends of the packages leave the uppermost bristles. The upper ends of the packages then fall upon the active flight of conveyor 40, while the lower ends slide over the upper end of the left hand brush body 21, 25 as viewed in Fig. 3, and the row of packages is then removed by the conveyor for suitable disposition, such as arrangement for packing in boxes or otherwise, as may be desired. To facilitate the sliding of the packages 30 over the brush body 21 and their delivery onto the conveyor the upper edge of the left hand brush body may be provided with a downwardly beveled surface 50, which reduces the upper edge contact of 35 the body with the packages and facilitates downward and outward movement of the rear ends of the packages over the brush body and onto the conveyor. The carry-off conveyor may be driven in any suitable way, 40 for instance, by interconnection with any suitable driving part of the present mechanism; but this is not essential and the driving connection may be to a part of the subsequent handling mechanism, or otherwise, 45 as may be desirable.
- One end of conveyor 12 may be carried by a pulley 60, fixed on a shaft 61. The belt may extend to the right as seen in Fig. 1 to any suitable point where that end of the 50 belt may be supported by another pulley, not shown. Adjacent to shaft 61 is a drive shaft 63 and between these shafts is an intermediate shaft 64 which carries a gear 65 meshing with a pinion 66 on shaft 61.
- Means for driving shaft 64 intermittently from continuously rotating shaft 63 are provided, consisting in the present embodiment of the following: One face of gear 65 is provided with a plurality of pairs of 65 parallel flanges 67, defining radial channels 68 open at their outer ends. Shaft 63 carries an arm 70 on which is a roller 71 adapted to co-operate with channels 68. In the position shown in Fig. 1 the roller has just left the adjacent channel 68. The conveyor is at rest and remains so during considerably more than one-half revolution of shaft 63. At the completion of this movement roller 70 enters the open end of channel 68 which is directed upward diagonally 75 toward the right, and engages the lower flange 67 of the channel and thus rotates gear 65 one-fifth revolution. This motion is suitably multiplied by gear 65 and pinion 66, and shaft 61 and pulley 60 are thus 80 turned sufficiently to move the conveyor belt forward one step to bring a new row of packages into labeling, brushing and feeding position.
- It is desirable to provide means for positively retaining the conveyor in position during its period of rest. For this purpose in the present embodiment shaft 61 is provided with a cross piece 75 having short arc-shaped ends 76 in which are provided, at 85 diametrically opposite points, notches 77. A rock-arm 78, which may conveniently be movably mounted on shaft 64 is provided with a tooth 79 to co-operate with notches 77. The other end of the rock-arm has a 90 roller 80 co-operating with the periphery of a cam body 81 fixed on shaft 63. This cam body has a substantially semi-circular concentric portion 82 and another substantially semi-circular concentric portion 83 of 95 smaller diameter, these portions being connected by a suitable curvature of the cam periphery. Shortly before roller 70 leaves one of the channels 68 at the end of each feed movement of the conveyor, the large 100 concentric portion 82 of cam 81 leaves roller 80 and rock-arm 78 rotates until its tooth 79 engages the adjacent notch 77 of cross piece 75. Pulley 60 is thus locked in position by the tooth until the next feed movement is about to take place, at which time cam roller 80 is forced down until it rides again on the large concentric portion 82 of the cam and tooth 79 is withdrawn from the notch at about the time that roller 71 enters 110 another channel 68 and thereupon another feed movement is made as previously described. The end of arm 78 carrying tooth 79 may be made sufficiently heavy to rotate to engage the tooth with the appropriate 115 notch whenever that movement is permitted by cam 81, or a spring may be provided for this purpose when necessary or desirable.
- Brush frame 20 is reciprocated in proper 120 relation to the conveyor movement by suitable mechanism such as the following: A cam body 85 is mounted on a shaft 86 carried by suitable bearings supported by frame 11. This shaft is connected to shaft 130

63, to move at the same speed, by a chain 87 and sprockets carried by the respective shafts. The cam body has a cam channel 88 in which engages a cam roller 89 mounted 5 on one arm of a lever 90, which is fulcrumed at 91 on a part of the frame. The other end of the lever is connected by a link 92 to the lower end of upright 30. The cam groove is arranged so that downward movement of brush 20 commences at about the time the conveyor comes to rest and the frame completes its downward and return movement during the rest movement of the conveyor and then the brush frame is held 10 up by the cam until another row of packages is brought into position by the conveyor.

The moving parts may be driven in any suitable way, for instance, a drive pulley may be placed on either shaft 86 or shaft 63, 20 or either of these shafts may be connected to another moving part of a complete machine of which mechanism constituting the present invention may be an operative part.

Figs. 4 and 5 show modified means for dis- 25 charging packages or rows of packages from the brush mechanism. According to this modification each downward stroke of the combined brush and feed device leaves a row of packages P projecting considerably above 30 the brush members. At the next upward movement this row passes between parallel vertical guide members 100 carried by a suitable slotted frame 101 which is in turn supported by uprights 102, connected to the 35 main frame of the machine, or to the table. The vertical guides may be slotted as in the case of guides 15, providing openings 103 to accommodate rows of brush bristles so that the guide members do not interfere with the 40 complete upward movement of the brushes. The vertical guide members may be made of thin spring metal and shaped to yieldingly grip the packages so that at the next downward movement of the brush frame a row 45 of packages is retained between the guides as shown in Fig. 5. The next upward movement of the brush frame causes the upper row of packages carried by the brushes to push up the row suspended in guides 100 50 until their lower ends lie parallel to the upper surfaces of a table 105 extending laterally from the upper end of the opening between guides 100. The table constitutes the bottom of a package channel, the sides of 55 which are defined by upright guide members 106. The lateral feed member, consisting of a plate 107, substantially co-extensive with the face of the package row, is now moved laterally to transfer the package row 60 bodily into the lateral channel. For this purpose feed plate 107 is mounted on an upright 108, the lower end of which is secured to horizontal bars 109—110. These bars are mounted in suitable horizontal guide-ways 65 carried by the main frame. One of the

guide bars 109 extends below the table to a point 112 where it is connected to a link 113, the other end of which is connected at 70 114 to a lever 115 fulcrumed at 116 to a fixed part of the frame. The other end of the lever is provided with a cam follower 117 engaging a cam groove 118 in body 119 which may be located on any suitable shaft, but conveniently is carried by shaft 63, Fig. 1. The cam groove is arranged so that feed 75 plate 107 is reciprocated during the period of rest of the brush frame at the upper end of its stroke.

A follower block 130 is located in lateral feed channel 106 to maintain the rows of 80 packages in the channel in upright position. To hold each row of packages as it is fed into the channel in proper position, a detent 135 is desirably provided. In the present case this consists of a sheet metal 85 plate having a downwardly bent end 136 overlapping the upper face of the package row. The plate is carried by an oscillating shaft 137 mounted on uprights 138 and provided with an operating arm 139. This arm 90 has a cam roller 140 engaged by a cam 141 pivoted at 142 on a block 143 carried by a rod 144 bolted to feed plate 107. Cam 141 is urged down by a spring 145 and its downward movement is limited by a suitable stop. 95 The cam has a beveled face 146 confronting cam roller 140. In the position shown in Fig. 4 detent 136 is in engagement with the last package row which has been inserted in the lateral feed channel. At the commencement of the next feed movement beveled face 146 of cam 141 raises cam roller 140, and detent 136 is thus elevated sufficiently to permit the new row of packages to move into the position shown in Fig. 5. During 100 this movement the cam roller rides over the upper surface of the cam and then drops below the right hand end of the cam. Feed plate 107 is then retracted and the lower surface of cam 141 rides up over the cam 110 roller, the cam pivoting upward against its spring to permit its return movement. At the end of the return movement the cam drops back into normal engagement with the cam roller as shown in Fig. 4. 115

It is evident from the foregoing that the combined label applying, or smoothing down and pressing, and package feeding device is an important novel feature of the invention which may be used in many different adaptations apart from the particular machine here shown. While the present invention is identified as labeling mechanism for want of a better term, it is not necessarily limited to applying labels, but may 120 be employed in any case where it is desired to apply or smooth or press down adhesive sheets upon articles, and at the same time to advance the articles successively toward another position. A desirable adaptation of 125 130

1 this feature of the invention is well illustrated in the present example in which the labels are, specifically, revenue stamps applied to cigarette packages. It is evident 5 also in a broader sense of the invention that it is not limited to operating upon rows of packages. Packages or articles may be handled one at a time, successively, by correspondingly simplified arrangement of the 10 mechanism.

Other features of the invention are also capable of embodiment in different forms, and no limitations to details of construction or arrangement are intended, except as expressed in the claims.

What we claim is:

1. In mechanism for applying adhesively coated labels and the like, a combined label applying and article advancing instrumentality comprising yieldable label applying and article gripping members, and means for moving the instrumentality to smooth down label portions upon successive articles and to feed the articles successively forward 20 in a row with the articles in contact, by the combined action of said instrumentality and of each successive article advancing into the instrumentality.

2. In mechanism for applying adhesively 30 coated labels and the like, a combined label applying and article feeding instrumentality, arranged to provide an article passage, comprising yieldable label applying and article gripping elements in the passage, and 35 means for moving the instrumentality to and fro to apply label portions to successive articles and advance the articles successively through said passage.

3. A movable label applying and article 40 feeding instrumentality providing an article passage, comprising flexible label pressing and article gripping members substantially forming two opposite walls of the passage, and means for moving the instrumentality to and fro to smooth down label portions upon successive articles and grip the articles and advance them successively 45 through the passage.

4. A combined label applying and article 50 feeding instrumentality comprising opposed brushes providing an article channel with brush members positioned to smooth down label portions upon articles and to grip successive articles and move them in one direction and to move freely over the articles in the opposite direction, and means for moving the instrumentality to and fro.

5. A combined label affixing and article 60 feeding instrumentality comprising bodies arranged to provide an article channel and brushing bristles diagonally arranged on the bodies and having their inner ends substantially defining two opposite walls of the channel, and means for reciprocating the instrumentality, whereby the bristles smooth 65

and press down label portions upon successive articles and grip the articles and advance them through the channel.

6. A combined label applying and article feeding instrumentality comprising side 70 members providing a passage of a length to accommodate a plurality of articles in end to end relation and flexible article-engaging and label applying members carried by one of the side members and arranged to substantially define one side of said passage, and means for moving said instrumentality to-and-fro.

7. A combined label applying and article feeding instrumentality comprising side 80 members of a length sufficient to accommodate between them a plurality of articles in end to end relation, a plurality of flexible diagonally arranged label applying and article feeding elements carried by one of the 85 side members, and means for reciprocating the instrumentality.

8. A combined label applying and article feeding instrumentality, comprising opposite side members of a length sufficient to 90 accommodate between them a plurality of articles in end to end relation and brush bristles diagonally arranged on the inner faces of the side members and forming substantially two opposite walls of an article 95 passage, and means for reciprocating the instrumentality so that the brush bristles act to smooth and press down label portions upon successive articles and to feed the articles successively through the passage in a 100 step by step movement.

9. A combined label applying and article feeding instrumentality comprising side members dimensioned to accommodate between them a plurality of rows of similar articles, and flexible elements extending inward from one of the side members and arranged to yieldingly engage the articles of successive rows and also to fold and press down label portions against the articles, and 105 means for moving the instrumentality to and fro.

10. A combined label applying and article feeding instrumentality comprising side members dimensioned to accommodate between them a plurality of rows of similar articles, diagonally arranged bristles fixed on the side members and constituting substantially two sides of an article passage, and means for reciprocating the instrumentality.

11. Labeling mechanism comprising means for positioning a row of articles having labels initially attached, a combined label applying and article feeding instrumentality providing an article passage and comprising means for smoothing and pressing label portions upon the articles and simultaneously gripping the articles to remove them from the positioning means, and means 125 130

- for moving said instrumentality toward and from the positioning means.
12. A labeling machine comprising means for positioning a row of similar articles having partially attached labels, and a combined label attaching and article feeding instrumentality comprising side members adapted to be moved down over the article row and yieldable label applying and article gripping means carried by one of the side members, and means for moving the instrumentality toward and from the positioning means to operate upon and remove successive rows of articles.
13. A labeling machine comprising means for positioning successive rows of articles having initially applied labels, a combined label applying and article feeding instrumentality comprising side members provided with diagonally arranged brush elements constituting substantially an article channel dimensioned to accommodate a plurality of rows of articles, and means for moving the instrumentality toward and from the positioning means whereby the brushing element smooth down label portions upon articles of successive rows and grip and feed the rows of articles successively between the side members in a step by step movement.
14. A labeling machine comprising means for positioning successive rows of articles having initially applied labels, a combined label applying and article feeding instrumentality comprising side members provided with diagonally arranged brush elements constituting substantially an article channel dimensioned to accommodate a plurality of rows of articles, means for moving the instrumentality toward and from the positioning means whereby the brush elements smooth down label portions upon articles of successive rows and grip and feed the rows of articles successively between the side members in a step by step movement, and means for deflecting articles ejected from said instrumentality.
15. A labeling machine comprising means for positioning successive rows of articles having initially applied labels, a combined label applying and article feeding instrumentality comprising side members provided with diagonally arranged brush elements constituting substantially an article channel dimensioned to accommodate a plurality of rows of articles, means for moving the instrumentality toward and from the positioning means whereby the brushing elements smooth down label portions upon articles of successive rows and grip and feed the rows of articles successively between the side members in a step by step movement, and means for carrying off rows of articles ejected from said instrumentality.
16. A labeling machine comprising means for positioning successive rows of articles having initially applied labels, a combined label applying and article feeding instrumentality comprising side members provided with diagonally arranged brush elements constituting substantially an article channel dimensioned to accommodate a plurality of rows of articles, means for moving the instrumentality toward and from the positioning means whereby the brushing elements smooth down label portions upon articles of successive rows and grip and feed the rows of articles successively between the side members in a step by step movement, and means for carrying off rows of articles ejected from said instrumentality.
17. A labeling or like machine comprising a belt conveyor, spaced article engaging members on the conveyor, means for advancing the conveyor intermittently, means for locking the conveyor intermittently, and a combined label affixing and article removing instrumentality providing an article channel for the passage of a series of articles in contact and comprising yielding article feeding and label pressing means, and means for moving said instrumentality in regularly timed relation to movements of the conveyor toward and from the conveyor to remove articles from the conveyor, advance them through said passage and press labels upon the articles.
18. A labeling or like machine comprising a belt conveyor, a shaft, a conveyor pulley on the shaft, a drive shaft, an intermediate shaft geared to the pulley shaft and provided with radial channels, a member carried by the drive shaft and adapted to cooperate with the channels successively to impart a step by step movement to the conveyor belt, and a combined label affixing and article removing instrumentality providing an article channel for the passage of a series of articles in contact and comprising yielding article feeding and label pressing means, and means for moving said instrumentality in regularly timed relation to movements of the conveyor toward and from the conveyor to remove articles from the conveyor, advance them through said passage and press labels upon the articles.
19. A labeling or like machine comprising a belt conveyor, means for intermittently driving the conveyor, means for intermittently locking the conveyor including a cam operated detent, and a combined label affixing and article removing instrumentality providing an article channel for the passage of a series of articles in contact and comprising yielding article feeding and label pressing means, and means for moving said instrumentality in regularly timed relation to movements of the conveyor toward and from the conveyor.

the conveyor to remove articles from the conveyor, advance them through said passage and press labels upon the articles.

20. A labeling or like machine comprising means for positioning a row of articles, a combined label applying and article feeding instrumentality comprising side members and brush bristles projecting inwardly between the side members, means for

10 moving the instrumentality toward and from the positioning means, and guide members for the article row adjacent to the positioning means and provided with openings to accommodate certain of the brush bristles.

15 21. A labeling or like machine comprising a conveyor for positioning successive rows of articles, a combined label applying and article feeding instrumentality comprising a frame, an enclosure carried by the frame

20 and dimensioned to accommodate a plurality of rows of articles in superposed endwise relation, a plurality of groups of rows of brush bristles carried by opposite sides of the enclosure and inclined diagonally

25 ly in the direction of feed, and means for reciprocating said instrumentality toward and from the conveyor in timed relation to the conveyor movement.

22. A labeling or like machine comprising a conveyor for positioning successive rows of articles, a combined label applying and article feeding instrumentality comprising a frame, an enclosure carried by the frame and dimensioned to accommodate a plurality of

35 rows of articles in superposed endwise relation, a plurality of groups of rows of brush bristles carried by opposite sides of the enclosure and inclined diagonally in the direction of feed, a vertical member supporting

40 said frame, guides for the vertical member, and means for moving the vertical member in timed relation to the conveyor movement.

23. A labeling or like machine comprising a conveyor for positioning successive rows of articles, a combined label applying and article feeding instrumentality comprising a frame, an enclosure carried by the frame and dimensioned to accommodate a plurality of rows of articles in superposed endwise re-

50 lation, a plurality of groups of rows of brush bristles carried by opposite sides of the enclosure and inclined diagonally in the direction of feed, means for moving the frame

toward and from the conveyor and vertical article row guide members adjacent to the 55 conveyor forming substantially a guide trough for the article row, said guide members having spaced openings to accommodate certain of the groups of brush bristles and permit a full downward movement of 60 said instrumentality.

24. A labeling or like machine comprising a conveyor, means for driving it intermittently, guides for a row of articles at one point adjacent to the conveyor, a frame, an 65 enclosure carried by the frame, a plurality of groups of brush bristles carried by two opposite sides of the enclosure and arranged diagonally with their inner ends constituting substantially an article passage 70 dimensioned to accommodate a plurality of superposed rows of articles, and means for moving the frame toward and from the conveyor to initially brush down ends of adhesive labels affixed to the tops of a row of 75 articles thereon and successive movements of the frame then acting to feed the rows of articles successively up through the article passage.

25. A labeling or like machine comprising 80 a conveyor, means for driving it intermittently, guides for a row of articles at one point adjacent to the conveyor, a frame, an enclosure carried by the frame, a plurality of groups of brush bristles carried by two 85 opposite sides of the enclosure and arranged diagonally with their inner ends constituting substantially an article passage dimensioned to accommodate a plurality of superposed rows of articles, means for moving the frame 90 toward and from the conveyor to initially brush down ends of adhesive labels affixed to the tops of a row of articles thereon and successive movements of the frame then acting to feed the rows of articles successively 95 up through the article passage, a lateral support to receive rows of articles discharged from the upper end of said passage, and means for directing rows of articles onto said lateral support.

Signed at New York city, in the county of New York and State of New York, this 18 day of November A. D. 1920.

JOHN A. OLSON.
JOHN E. WILLIAMSON.
